US0D1076247S

(12) **United States Design Patent** (10) **Patent No.:** **US D1,076,247 S**
(45) **Date of Patent:** **** May 20, 2025**

(54) **PET BED**

(71) Applicant: **Zhonghui Yang**, Taicang (CN)

(72) Inventor: **Zhonghui Yang**, Taicang (CN)

(**) Term: **15 Years**

(21) Appl. No.: **29/956,279**

(22) Filed: **Aug. 6, 2024**

(30) **Foreign Application Priority Data**

Aug. 2, 2024 (CN) 202430487959.7

(51) **LOC (15) Cl.** **30-06**

(52) **U.S. Cl.**

USPC **D30/118**

(58) **Field of Classification Search**

USPC D30/108, 112, 118, 119; D6/331, 390,
D6/391, 392

CPC A01K 1/0353; A01K 1/0272
